The center portion of the design is surrounded by the vine arch-frame *h*, wheel figures *i*, and the chain *j*, connecting the wheel figures, the wheel figures being located in the lower corners of the open fret-work, and the arch-frame resting on said wheel figures, and having leaf branches *k* and flower branches *l*, reaching outward and joining the rim *m*, having an ornamental chain border, *n*, on the inner margin.

I claim—

2. In a design for a hot air-register front 30 berein shown, the center portion of the open fret-work surrounded by an outer portion consisting of the vine arch-frame *h*, wheel figures *i*, chain *j*, and the border-chain *n*, said chain *j* connecting the wheel figures *i*, which are located in the lower corners of the fret-work, and the vine arch-frame resting on said wheel figures, and having branches *k* and *l*, reaching outward and joining the rim *m*, having the chain *n* on its inner margin, as set forth. 35 40
